UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY.

IGNITION APPARATUS.

1,363,742.

Specification of Letters Patent. Patented Dec. 28, 1920.

Application filed April 6, 1920. Serial No. 371,753.

To all whom it may concern:

Be it known that I, CHARLES T. MASON, a citizen of the United States, residing at Sumter, in the county of Sumter, State of 5 South Carolina, have invented certain new and useful Improvements in Ignition Apparatus, of which the following is a description, reference being had to the accompanying drawing and to the figures of reference 10 marked thereon.

This invention relates to new and useful improvements in ignition apparatus, more particularly to an ignition device having a fixed and movable electrode adapted to co- 15 operate with each other within an engine cylinder. The current is supplied to the electrodes by an ignition generator of the magneto type.

One of the objects of the invention is to 20 provide an ignition apparatus of the above character, wherein two unitary structures are involved, one of which is an integral bracket having two portions, one of which is substantially at right angles to the other and 25 one of which portions carries the electrodes. The other unitary structure consists of the magneto generator with certain parts permanently fixed thereto but which coöperate with the electrodes when the two unitary 30 structures are brought together.

A further object of my invention is to provide two unitary structures as above set forth which may be easily and quickly placed in coöoperative relationship and the operating 35 connections between the two structures are automatically made by the positioning of the magneto generator on the bracket.

Another object of my invention is to provide a device of the above character, wherein 40 there is no exposed flexible connections between the generator and the electrodes, as such flexible connections as have been used in the past give more or less trouble due to breakage and loose contacts from vibration, etc.

Another object of my invention is to provide a structure in which it is impossible to remove the bracket from the engine without first taking the magneto off the bracket.

Another object of my invention is to provide a trip lever mechanism for the current generating portion of the generator which is relatively simple but will give long life in operation.

Another object of my invention is to provide a housing for the moving parts so as to protect them from injurious agents.

Other and further objects will be apparent to one skilled in the art after study of the specification and drawings annexed thereto. 60

In the drawings, Figure 1 is a perspective view showing the complete assembled ignition apparatus.

Fig. 2 is a top view of Fig. 1 with a portion of the yoke member cut away. 65

Fig. 3 is an end view of Fig. 1 but with the vertical part of the bracket carrying electrodes removed, the lever for removing the movable electrode being shown in dotted position.

Fig. 4 is a left hand end view of the ignition generator and bracket.

Fig. 5 is a view of the bracket without the generator or electrodes mounted thereon, the view being taken from the backside of 75 Fig. 1.

Fig. 6 is a part sectional view through the fixed electrode and the vertical portion of the bracket.

Fig. 7 is a detailed view showing the 80 method of attaching the springs shown in Fig. 3.

Referring now to the details, wherein like numbers refer to corresponding parts in the various views, 1 is a bracket having two portions 2 and 3, which are preferably made integral one to the other and arranged substantially at right angles. The vertical portion 3 has a plug 4 through which pass a movable electrode 5 and a fixed electrode 6, 90 suitable insulators being used to insulate the electrode 6, as will be seen in Fig. 6. The plug portion 4 is adapted to fit within an engine cylinder so that the surface of the vertical portion 3 can be bolted against a 95 smooth surface on the engine by means of the bolts passing through holes 7 and 8. A part of the backside of the portion 3 projects rearwardly as indicated by the shoulder 9, the purpose of which will be hereinafter 100 referred to.

Joining the portions 2 and 3 of the bracket 1 on the backside (see Fig. 1) is a web flange 10, which greatly increases the strength of the bracket, at the same time conceals or masks the hole 8 so that when the generator is on the bracket it is impossible to get at the bolt passing through the

hole 8, making it necessary to remove the generator from the bracket before taking the bracket from the engine. The horizontal portion 2 of the bracket is strengthened 5 at the center by a boss 11. The boss 11 is slotted longitudinally as indicated at 12 for the reception of set screws 13 and 14, which are used to fasten the magneto 15 to the bracket. The current generating member 10 has its shaft extended and carries thereon a trip lever 16 which has a notch 17 for the reception of an engine actuating lever which operates the member 16 in a well known manner. Fastened to the generator frame, 15 adjacent to the trip lever 16 is a yoke 18, which has a portion 19 bent over and extending laterally therefrom toward the vertical member 3 and adapted to fit over the shoulder 9. Ears 20 are formed of this 20 laterally extending portion of the yoke 18, which serve as supports for the pins 21 on which are carried collars 22, which have holes 23, much larger than the pins 21 for the purpose hereinafter referred to. The 25 one end of springs 24 are bent around grooves in the collars 22, while the other end of the springs 24 are attached to corresponding pins 25 on the trip member 16. The movable electrode 5 carries a lever 26 30 adapted to be engaged by the cam nose 27 of trip lever 16. A spring 28 is also carried by the movable electrode so as to normally hold the contacts 29 normally closed. When the apparatus is in normal position 35 the trip lever 16 is not in engagement with the lever 26.

In previous types of ignition generators of this character it has been customary to bring the insulated terminal of the generating coil to the movable electrode or a co-operating contact by a flexible conductor. These become broken and are shaken loose and in order to get away from this trouble, I have brought the insulated end of the current generating coil out through the shaft of the generator by means of a suitable contact rod 30. As will be seen by referring to 40 Fig. 1, the center line of the shaft of the generator and the center line of the electrode 6 are not in the same straight line but are spaced apart some distance, therefore, in order to make the connection between the armature contact 30 and the fixed electrode 6, I have mounted on the back part of the 45 portion 3 of the bracket a suitable insulator 31, which carries a contact strip 32 having a contact 33 adapted to engage the contact 30. The back of the portion 3 is cut away at 34 to allow certain movements of the member 32 and contact 33 without any danger of grounding these parts or the electrode 6 to the bracket. The members 32 and 50 33 are so proportioned and arranged that the contact 33 comes in line with the armature contact 30.

It will readily be seen that by slightly loosening the set screws 13 and 14 the magneto 15 can be readily slipped off the bracket and for the same reason it can be easily put back on, stop pins 35 being provided so as 70 to limit the movement of the generator 15 so that the contact 32 and member 33 cannot be forced out of the position intended for them.

It will be seen from Fig. 2 that the portion 19 of the yoke 18 fits over the upper part of the flange 10 and that the trip lever 16, springs 24, lever 26 and spring 28, as well as the contacts 30—33 are protected from dust and dirt falling from above, 80 which is highly advantageous as an accumulation of dust and dirt on these members cause rapid wear.

The operation of my device can be readily understood so it may only be briefly referred 85 to; as previously stated, an engine operating lever engaging the notch 17 of the trip lever 16 causing the same to operate and tensioning the springs 24 until the nose 26 pushes the operating lever out of the notch 90 17 allowing the springs 24 to return the trip lever 16 suddenly to its normal position, but as will be understood the overthrow causes the nose 27 to hit the lever 16 a sudden impulse, separating the contacts 29 at the time 95 of maximum current generation in the generator coil.

For the purpose of starting the engine, I have extended the generator shaft through the opposite end of the generator and have 100 fastened thereto a lever 36, which may be engaged by the operative finger for the purpose of pulling the current generating member and trip lever 16 to a position whereby, when the lever 36 is released, a spark will be 105 produced at the contacts 29.

By the construction shown in detail in Fig. 7, I secure a rolling motion between the roller 22 and the pin 21 with little or no movement of the end of the spring on the 110 roller so that long life is obtained by this improved construction.

While I have shown and described one form of my invention, it will be apparent that numerous changes may be made in the 115 various details without departing from the spirit of my invention and the scope of the appended claims.

Having thus described my invention what I claim is:—

1. In an ignition device, the combination 120 of a bracket, a fixed and a movable electrode mounted therein, a magneto generator having a shaft carrying a current generating member mounted on said bracket, a trip lever attached to one end of the generator shaft, a yoke carried on the generator adjacent said trip lever, springs attached to the opposite ends of said yoke and to the trip lever for actuating the same to operate the 125 130

movable electrode, said yoke having a part extending over and forming a cover for the trip lever and springs.

2. An ignition apparatus comprising in combination with an integral plug and bracket, a fixed and a movable electrode mounted in the plug portion and protruding on both sides thereof, a magneto generator having a shaft carrying a current generating member removably mounted on said bracket, a trip lever attached to one end of the generator shaft, a yoke fastened to the generator adjacent said trip lever and having a portion extending longitudinally over the trip lever and one end of said electrodes and springs attached to the opposite ends of said yoke and to the trip lever for actuating the same to operate the movable electrode as described. -

20 3. In an ignition device the combination of, an integral bracket having horizontal and vertical portions, a fixed and a movable electrode mounted in the vertical portion and extending through both sides thereof, a magneto generator having a shaft carrying a current generating member mounted on the horizontal portion of the bracket, a trip lever attached to the end of the generator shaft adjacent the vertical portion of the bracket, a yoke having a flat portion fastened to the generator adjacent the trip lever and a portion extending laterally from the flat portion into close proximity to the vertical portion of the bracket forming a housing for the trip lever and one end of said electrodes and springs fastened to one end of said yoke and trip lever under said housing for actuating the trip lever for the purpose described.

40 4. In an ignition device, the combination of, an integral bracket having horizontal and vertical portions, a fixed and a movable electrode mounted in the vertical portion and extending through both sides thereof, cooperating contacts on one end adapted to function within an engine cylinder, a lever and retracting spring on the other end of the movable electrode, a magneto generator having a shaft carrying a current generating member mounted on the horizontal portion of the bracket, a trip lever attached to the generator shaft in position to operate the lever on the movable electrode, but normally out of engagement therewith, a yoke fastened to the generator adjacent the trip lever, springs attached to the opposite ends of said yoke and trip lever for actuating the same into engagement suddenly with the lever on the movable electrode, said yoke having a portion extending laterally from the body of the yoke forming a housing over the said springs, trip lever and electrode lever and retracting spring.

5. In an ignition device the combination of, an integral bracket having a horizontal

and vertical portion with holes therein for mounting on an engine cylinder and a web flange uniting with the two portions at a point whereby at least one of said mounting holes is masked for the purpose described, 70 a fixed and a movable electrode mounted in said vertical portion and having projecting ends, a shoulder on the vertical portion, a magneto generator having a shaft carrying a current generating member mounted on said 75 horizontal portion, a trip lever attached to the end of the generator shaft, a yoke fastened to the generator adjacent the trip lever, springs attached to opposite ends of the yoke and the lever for suddenly actuating the same, said yoke having a portion extending laterally into close proximity to the vertical portion and over said shoulder and upper part of said flange forming a housing 80 for said springs, trip lever and one end of 85 said electrodes.

6. In an ignition device the combination of, an integral bracket having two portions, one horizontal and one vertical, said vertical portion carrying a fixed and a movable 90 electrode having contacts on one end adapted to enter an engine cylinder, a magneto generator having a shaft carrying a current generating member with one end of the current generating coil brought through and to the end of said shaft, a trip lever carried on the shaft, a yoke fastened to the generator frame adjacent the trip lever, springs attached to the yoke and trip lever for suddenly actuating the same, said yoke having 100 a portion extending over said springs and trip lever, set screws for fastening the generator to said horizontal portion of the bracket, a slot in said horizontal portion for slidably moving thereon said generator 105 when the set screws are loosened, means on said vertical part for connecting automatically the fixed electrode to said contact on the end of the shaft when the generator is slid into position on the bracket and means 110 on the movable electrode adapted to be acted on by the trip lever for operating said contacts.

7. In an ignition device, the combination of, an integral bracket having two portions 115 substantially at right angles to each other, a fixed and a movable electrode carried on one portion of the bracket, a magneto generator having a shaft carrying a current generating member with one end of the 120 current generating coil brought through and to the end of said shaft, said shaft and fixed electrode being in different alignments, means carried by that portion of the bracket carrying the electrodes for automatically 125 completing connection between the said shaft contact and the fixed electrode when the generator is moved into place on the bracket, a trip lever on the shaft for actuating the movable electrode, a yoke on the 130

generator and springs co-acting between the yoke and trip lever to suddenly actuate the same as described.

8. In an ignition device, the combination of, an integral bracket having two portions substantially at right angles to each other, a fixed and a movable electrode carried in one portion and an ignition generator carried on the other portion, said generator having its generating coil terminal brought out to a contact on the end of its shaft, co-acting means carried on the generator and its shaft for oscillating said shaft and current generating member carried thereon, means on the movable electrode for coöperation with said co-acting means and means carried on that portion of the bracket carrying the fixed electrode for making a yielding electrical connection with said shaft contact when the generator is in operating position on the bracket.

9. In an ignition device the combination of, a magneto generator having a shaft carrying a current generating member and a contact on the end of the shaft, said contact being electrically connected to the current generating coil, a trip lever carried on said shaft, a bracket having a part adapted to be bolted to an engine, said part carrying a fixed and a movable electrode and another part adapted to receive said generator, means on the movable electrode for holding the electrodes normally in contact and further means for coöperating with said trip lever, means on the part of the bracket bolted to the engine for automatically engaging the shaft contact when the generator is in operating position on the bracket and means carried on the generator for giving an impulse to the trip lever for the purpose described.

10. In an ignition device the combination of, a magneto generator having a shaft carrying a current generator member and a contact on the end of the shaft, said contact being electrically connected to the current generating coil, a trip lever carried on said shaft, a bracket having a part adapted to be bolted to an engine, said part carrying a fixed and a movable electrode and another part adapted to receive said generator, means on the movable electrode for holding the electrodes normally in contact and further means for coöperating with said trip lever, means on the part of the bracket bolted to the engine for automatically engaging the shaft contact when the generator is in operating position on the bracket, means carried on the generator for giving an impulse to the trip lever and means on the bracket for definitely positioning the generator thereon so that said automatic engagement means cannot be forced out of operative position when the generator is stalled.

11. In an ignition device the combination of, a magneto generator having a shaft carrying a current generating member and a contact on the end of the shaft, said contact being electrically connected to the current generating coil, a trip lever carried on said shaft, a bracket having a part adapted to be bolted to an engine, said part carrying a fixed and a movable electrode and another part adapted to receive said generator, means on the movable electrode for holding the electrodes normally in contact and further means for coöperating with said trip lever, means on the part of the bracket bolted to the engine for automatically engaging the shaft contact when the generator is in operating position on the bracket, a yoke on the generator, springs fastened to the yoke and trip lever for giving an impulse to said trip lever at the proper time and a cover preferably formed integral with the yoke for the trip lever and co-acting mechanism.

12. In an ignition device the combination of, a magneto generator having a shaft carrying a current generator member and a contact on the end of the shaft, said contact being electrically connected to the current generating coil, a trip lever carried on said shaft, a bracket having a part adapted to be bolted to an engine, said part carrying a fixed and a movable electrode and another part adapted to receive said generator, means on the movable electrode for holding the electrodes normally in contact and further means for coöperating with said trip lever, means on the part of the bracket bolted to the engine for automatically engaging the shaft contact when the generator is in operating position on the bracket and means carried on the generator for giving an impulse to the trip lever, said generator having its shaft extending at the end opposite from said contact and a lever fastened to said shaft end for actuating said current generating member and impulse means at will.

13. An ignition apparatus comprising in combination, two unitary structures, a generator having a shaft carrying a current generating member and a trip lever with springs for giving a sudden impulse to both; an integral bracket having a vertical portion adapted to be fastened to an engine cylinder and a horizontal portion with a fixed and a movable electrode mounted in the vertical portion and a web flange joining said two portions on the non-operating side of the bracket whereby said bracket cannot be removed from the engine until said generator has been removed from the horizontal portion thereof and means for automatically electrically connecting the fixed electrode with the current generating coil when the generator is put into operative

position on the horizontal portion of the bracket.

14. An ignition apparatus comprising in combination, two unitary structures, a bracket having two portions substantially at right angles to each other, one portion having a plug with a fixed and a movable electrode mounted therein and having means for fastening to an engine cylinder, the other portion having a reinforcing slotted rib to receive set screws for holding thereto a second unitary structure; said second unitary structure consisting of, an ignition generator having a shaft carrying, a current generating member, a contact at the shaft end, a trip lever and springs for giving a sudden impulse to the trip lever and connected mechanism and means coöperating between the fixed electrode and shaft contact to complete an electrical circuit through said electrodes when the generator is placed in operative position on the bracket.

15. An ignition apparatus comprising in combination, two unitary structures; a bracket having two portions substantially at right angles to each other, one portion having a plug with a fixed and a movable electrode mounted therein and having means for fastening to an engine cylinder, the other portion having a reinforcing slotted rib to receive set screws for holding thereto a second unitary structure; said second unitary structure consisting of, an ignition generator having a shaft carrying, a current generating member, a contact at the shaft end, a trip lever and springs for giving a sudden impulse to the trip lever and connected mechanism and means coöperating between the fixed electrode and shaft contact to complete an electrical circuit through said electrodes when the generator is placed in operative position on the bracket, said springs being fastened at one end to a yoke member and at their other ends to said trip lever, said yoke member being formed to provide a cover over the trip lever, springs and electrode contact.

16. In an ignition apparatus, a one piece bracket having vertical and horizontal portions, a fixed and a movable electrode mounted in the said vertical portion with means on the movable electrode for moving the same in one direction and other means for returning it to normal position, an ignition generator slidably mounted on the horizontal portion with automatic means for connecting the generating coil of said generator to said fixed electrode when the generator is slid into operative position, a trip lever for actuating the current generating member of the generator and the first mentioned means on the movable electrode, a yoke carried on the generator and springs positioned between the yoke and trip lever for imparting a sudden impulse to the same

after said springs have been tensioned, as described.

17. In an ignition apparatus, a one piece bracket having vertical and horizontal portions, a fixed and a movable electrode mounted in the said vertical portion with means on the movable electrode for moving the same in one direction and other means for returning it to normal position, an ignition generator slidably mounted on the horizontal portion with automatic means for connecting the generating coil of said generator to said fixed electrode when the generator is slid into operative position, a trip lever for actuating the current generating member of the generator and the first mentioned means on the movable electrode, a yoke carried on the generator and springs positioned between the yoke and trip lever for imparting a sudden impulse to the same after said springs have been tensioned, said yoke having a part bent over and fitting around a portion of the vertical part of the bracket forming a housing for the trip lever and directly coöperating mechanism.

18. In an ignition apparatus of the plug oscillator type, a bracket carrying a pair of electrodes having normally closed contacts and a generator connected in a permanently closed circuit including said contacts, a trip lever for actuating the moving element of the generator and one of said contacts, a yoke member having springs connected thereto and to said trip lever for imparting a sudden impulse thereto after said springs have been tensioned, said connection of the spring to the yoke consisting of; an ear formed from a part of the yoke, a pin extending through the ear and the end of the yoke and a grooved bushing for the spring carried on the pin, said bushing having an enlarged hole whereby a rolling action on the pin is obtained without movement of the spring in the groove as described.

19. In an ignition apparatus of the plug oscillator type, a bracket carrying a pair of electrodes having normally closed contacts and a generator connected in a permanently closed circuit including said contacts, a trip lever for actuating the moving element of the generator and one of said contacts, a yoke member having springs connected thereto and to said trip lever for imparting a sudden impulse thereto after said springs have been tensioned, said connection of the spring to the yoke consisting of; a pin supported on the end of the yoke and a grooved bushing carried on the pin, said bushing having a larger hole than the pin whereby a rolling action is obtained between the bushing and the pin without movement of the spring in the groove.

In testimony whereof, I affix my signature.

CHARLES THOMAS MASON.
